UNITED STATES PATENT OFFICE.

FRANK A. BURGESS, OF GENEVA, ILLINOIS, ASSIGNOR TO BURGESS-NORTON MANUFACTURING COMPANY, OF GENEVA, ILLINOIS, A CORPORATION OF ILLINOIS.

HATCHET.

1,089,043.

Specification of Letters Patent.

Patented Mar. 3, 1914.

Application filed February 14, 1913. Serial No. 748,292.

To all whom it may concern:

Be it known that I, FRANK A. BURGESS, a citizen of the United States, and a resident of Geneva, in the county of Kane and State of Illinois, have invented certain new and useful Improvements in Hatchets; and I do hereby declare that the following is a full, clear, and exact description thereof, reference being had to the accompanying drawings, and to the letters of reference marked thereon, which form a part of this specification.

This invention relates to hatchets having a metallic body or head and a metallic handle overlapping the head and provided with a reinforcement secured to the handle and in overlapping engagement with the head.

The principal object of the invention is to provide a simple, economical and efficient metallic hatchet.

Other and further objects of the invention will appear from an examination of the following description and claims and from an inspection of the accompanying drawings.

The invention consists in the features, combinations, and details of construction herein described and claimed.

In the accompanying drawings, Figure 1 is a side view of a hatchet constructed in accordance with my improvements, with a portion of the handle broken away to show the construction of the interior portion of the reinforcement between the head or body of the hatchet and the handle; Fig. 2, a horizontal sectional view, taken on line 2 of Fig. 1, through the head and the portion of the handle secured to the head or hatchet body, with a portion of the handle broken away; Fig. 3, a view in sectional elevation, taken on line 3 of Fig. 1, looking in the direction of the arrow; Fig. 4, a detail view in perspective of the metallic reinforcing member which is secured in overlapping engagement with the head between the head and overlapping portions of the handle; Fig. 5, a view in sectional elevation, taken on line 5 of Fig. 1 looking in the direction of the arrow; Fig. 6, a detail view in sectional elevation, showing the tubular portion of the inner reinforcement, and the tubular portion of a metallic handle formed of sheet metal with the edges of the tubular portion of the reinforcement in abutting engagement and brazed together on one side

of the handle, and the edges of the tubular portion which forms the handle in abutting engagement on the opposite side or bottom of the handle and brazed together; Fig. 7, a detail sectional view of the tubular portion of a metallic reinforcing member formed in two pieces having abutting edges on opposite sides of the handle or in diametrically opposite portions; and Fig. 8, a detail view in cross-section of the tubular portion of a metallic reinforcement formed of two pieces of sheet metal having overlapping marginal portions upset or brazed together, and adapted to be mounted in the hollow portion of a tubular metallic handle.

In constructing a hatchet in the form illustrated in the drawings in accordance with my invention and improvements, I provide a head or hatchet body, which comprises a hammer portion *a* and blade *b* secured to or forming a part of the hammer portion. The hammer portion and blade portion of the head are, by preference, made in separate parts, the hammer portion being provided with side pieces *c* and *d* which extend rearwardly from the hammer face and have a space *e* therebetween into which the shank or butt end of the blade extends. The side pieces *c* and *d* are provided with perforations *f* therethrough which register with perforations *g* in the blade member, and rivets *h* or similar securing means extend through said perforations and through the reinforcing member and handle hereinafter described, for securing all of said parts together (see Figs. 1, 2 and 3).

A handle *i*, formed, by preference, of a single piece of sheet metal bent into tubular form and having its margins *j* by preference in abutting engagement with each other and extending longitudinally of the handle, is secured in overlapping engagement with the head or hatchet body, the handle being provided with forked end portions *j* which extend in overlapping engagement with the head or hammer and blade members of the head or hatchet body on opposite sides thereof. The forked end portions or side pieces *j* of the handle are each provided with perforations *k* which register with the perforations *f* in the rearwardly projecting forked end or side pieces of the hammer member and with the perforations *g* in the blade member and through which the rivets *h* extend, as already suggested.

A reinforcing member, made by preference of sheet metal and comprising a tubular main body portion or shank *l* having integral forked end portions or side pieces *m*, is mounted in the forked end of the handle in such position that the tubular portion *l* of the reinforcement fits snugly into the hollow portion of the handle member *i*, and the forked portion or cheek plates *m* extend on opposite sides of the head in overlapping engagement with the hammer member and blade member of the head and between the head and handle, or, in other words, between the head and the overlapping portions *j* of the handle on opposite sides of the head. These forked end portions *m* are provided with perforations *n* therethrough which register with the perforations *t* in the hammer member and the perforations *g* in the blade member of the head or hatchet body, and the rivets *h* extend through the overlapping members *j* of the handle, the forked portions or side pieces *m* of the reinforcing member, the forked portions *c* and *d* of the hammer member, and the perforated portion of the blade *b*, so as to firmly secure said parts all together and hold them in rigid relation when subjected to the shocks and strains to which they are of necessity subjected in use.

The main body portion *l* of the reinforcing member is, by preference, made by bending a sheet of metal into tubular form, the sheet metal being cut to form end or forked arm portions *m* having an opening or slot therebetween for receiving the overlapped portions of the head and reinforcement, as shown in Fig. 4. The margins *o* of the tubular portion *l* are, by preference, diametrically opposite the marginal portions *j* of the tubular handle member so that the meeting edges of each of said members, respectively, are overlapped by a continuous unbroken portion of the other one of said members. These marginal portions *o* may be in abutting engagement with each other, as indicated in Fig. 4, and are adapted to be brazed so as to form a tube having continuous unbroken annular walls on the inside of the tubular handle member *i*. The reinforcing member may be brazed to the handle member *i* into the hollow portion of which it extends. The forked portions or side pieces *m* of the reinforcement extend on opposite sides of the head and between the head and forked end portions *j* of the handle, as shown in Figs. 2 and 3, and are, by preference, of sufficient width to overlap substantially all of the portions of the side pieces *c* and *d*, respectively, by which the blade is overlapped and supported. The forked portions *m* of the reinforcement are narrower than the overlapping parts *j* of the handle and the opposite margins *p* and *p'* of the latter are bent inward at an in-

clipe over and in position to snugly engage, inclose and conceal the adjacent edges of the forks *m* of the reinforcement, which thus fit snugly within and in rigid engagement with the inner concave sides of the concave forked arms or cheek plates *j* of the handle member. This not only gives a finished appearance to the tool but the tool is also rendered very strong and rigid by reason of the snugly fitting engagement between the margins of the forks of the reinforcement and the inwardly bent inclosing marginal portions *p* and *p'* of the outer overlapping forks or cheek plate portions of the handle member. The inwardly bent marginal portions *p* of the handle extend inward at an incline and into engagement with the opposite sides of the blade so as to form the sides of a wedge the point of which is formed by the blade. All of these parts are held together by the rivets *h* so as to brace and strengthen one another and form an exceedingly strong and rigid connection between the connected, overlapping parts.

In Fig. 6 the tubular portion *l* of the metallic reinforcement is shown with its margins in abutting engagement and diametrically opposite the abutting marginal portions *j* of the tubular handle *i*.

The tubular portion of the reinforcement, which is illustrated in Fig. 7, is formed of two side pieces *q*, each of which is integral with a forked end portion of the reinforcement adapted to extend in overlapping engagement with the hammer head and between the forked portions *j*, the marginal edges *r* of said side pieces being in abutting engagement and adapted to be brazed together, if desired, so as to form a metallic reinforcing member the shape of which, by preference, corresponds with the reinforcing member shown in Fig. 4.

In Fig. 8 is shown a tubular reinforcing member formed of side pieces *s* having adjacent marginal edges *t* in overlapping engagement with each other and adapted to be brazed together so as to form the tubular portion of a reinforcing member which is, by preference, of a form corresponding with that shown in Fig. 4.

It is manifest that the details of construction of a hatchet containing the general features herein set forth may be variously modified in practice without departing from the spirit of my invention, and I do not, therefore, desire to be limited to the particular features and details of construction illustrated or described, except in so far as the same may be pointed out in the appended claims.

I claim:

1. In a hatchet, the combination of a metallic head, a tubular metallic handle having forked end portions forming outer cheek

plates on opposite sides of and in overlapping engagement with the head, a reinforcing member fitting within the handle and having forked portions in overlapping engagement with the head and overlapped by said outer cheek plates on opposite sides of the head, and means for securing said parts all together.

2. In a hatchet, the combination of a metallic head, a tubular metallic handle having forked end portions forming outer cheek plates on opposite sides of the head, a reinforcing member fitting within the handle and having forked portions in overlapping engagement with the head on opposite sides thereof and of less width than the overlapping outer cheek plates of the handle, said outer cheek plates having marginal portions bent inward and inclosing the adjacent margins of the forked portions of the reinforcement, and means for rigidly securing said overlapping parts all together.

15 3. In a hatchet, the combination of a metallic head, a tubular metallic handle having forked end portions forming outer cheek plates on opposite sides of the head, a reinforcing member having a tubular portion fitting within the handle, and having forked portions integral with said tubular portion of the reinforcement extending on opposite sides of and in overlapping engagement with the head, said forked portions being of less width than the outer overlapping cheek plates of the handle member, said

30 35 40 cheek plates having their marginal portions bent inward into engagement with the head and into position to cover and inclose the edges of the forked portions of the reinforcing member, and common rivets each extending through the overlapping portions of all of said members.

4. In a hatchet, the combination of a metallic head comprising a hammer member and a blade member in overlapping engagement with each other, a tubular metallic handle having forked end portions forming outer cheek plates on opposite sides of and in overlapping engagement with the hammer member and blade, a reinforcing member fitting within the handle and having forked portions in overlapping engagement with the head and overlapped by the outer cheek plates on opposite sides of the head, and means for rigidly securing said parts all together. 55

5. In a hatchet, the combination of a metallic head comprising a hammer member and a blade member in overlapping engagement with each other, a tubular metallic handle having forked end portions forming outer cheek plates on opposite sides of and in overlapping engagement with the hammer member and blade, a sheet metal reinforcing member having a tubular shank fitting within the handle and having forked portions in overlapping engagement with the head on opposite sides thereof and of less width than the overlapping outer cheek plates of the handle, said outer cheek plates having marginal portions bent inward into engagement with and inclosing the adjacent edges of the forked portions of the reinforcement, and connecting means adapted to rigidly connect all of said overlapping parts. 60 70

In testimony that I claim the foregoing as my invention I affix my signature in the presence of two witnesses, this sixth day of Feby., A. D. 1913.

FRANK A. BURGESS.
